(57) **ABSTRACT**

An inflow control device and method of use. The device may include a chamber, wherein the chamber comprises a seat. The device may further include a fluid passageway fluidly connected to the chamber, an actuator disposed within the chamber, and a motor at least partially disposed in the chamber and detachably connected to the actuator by a detachable connector. The method of using the inflow control device may include receiving a fluid from a formation with an inflow control device (ICD) disposed on a tubular string within a formation and stopping flow of the fluid through the ICD by seating the actuator to the seat after the actuator has detached from the motor by the detachable connector.

FIG. 1

FIG. 2

FIG. 3

FIG. 4

FIG. 5

ELECTRIC INFLOW VALVE TO FULLY CLOSE AND THEN BE REOPENED WITHOUT DOWNHOLE INTERVENTION

BACKGROUND

Production tubing and other equipment can be installed in a wellbore of a well system (e.g., an oil or gas well) for communicating fluid in the wellbore to the well surface. The resulting fluid at the well surface is referred to as production fluid. Production fluid can include a mix of different fluid components, such as oil, water, and gas, and the ratio of the fluid components in the production fluid can change over time. This can make it challenging for a well operator to control which types of fluid components are produced from the wellbore. For example, it can be challenging for a well operator to produce mostly oil from the wellbore, while reducing or eliminating the production of gas or water from the wellbore.

BRIEF DESCRIPTION OF THE DRAWINGS

These drawings illustrate certain aspects of some of the embodiments of the present disclosure and should not be used to limit or define the method.

FIG. 1 is an elevation view of an example of a well system in which a flow control system may be implemented according to aspects of this disclosure.

FIG. 2 is an example of a power generator disposed in an inflow control device (ICD).

FIG. 3 is an example of an actuator disposed in an ICD.

FIG. 4 is a schematic of one or more ICDs with fluid flow within the ICD.

FIG. 5 is a schematic of one or more ICDs where fluid flow has stopped within the ICD.

DETAILED DESCRIPTION

A downhole flow control device is disclosed for controlling the production of formation fluids during operations. Generally, inflow control devices (ICDs) may be utilized to control the flow of fluid from the formation to the inner diameter of a tubing string. Certain ICDs may be electrical in nature and may be referred to as an electrical inflow control device (EICD). An EICD may operate from electricity produced from the flow of fluids from a formation to generate power. However, this limits the ability for an EICD to close fully and be easily reopened remotely. This is because if flow of fluids from the formation has been completely stopped through the EICD, then no more power is generated to operate the EICD, which prevents it from opening and allowing for fluid flow to resume. In examples, an energy storage device may be utilized to store energy onboard in some form. However, this overly complicates the overall system design and limits reliability. Additionally, energy storage devices may fail, and the stored energy may dissipate completely over time.

The methods and system discussed below may utilize an unbalanced actuator that upon being moved near the fully closed position via a drive mechanism, is subsequently pulled onto seat by fluid flow. Both the primary production flow along with the turbine generator flow all flow through the seat that may be blocked by the actuator, closing the EICD and preventing the flow of fluid through the EICD. If the EICD needs to be reopened later, the EICD may be reopened using injection flow to reset each into the open position and reengage them with the drive mechanism.

FIG. 1 is an elevation view of an example of a well system 100 in which a flow control system 140 may be implemented according to aspects of this disclosure. This figure is simplified in some respects for discussion and is not to scale.

Well system 100 includes a wellbore 102 extending through various earth strata of a subterranean formation 110. Wellbore 102 may follow any suitable wellbore trajectory to reach a desired production zone 111 of formation 110. The trajectory may include an initial vertical wellbore section 104 and one or more deviated sections employing directional drilling techniques. In this simplified example, wellbore 102 has an initial, substantially vertical section 104 that transitions to a substantially horizontal section 106 traversing production zone 111. Portions of the wellbore may be cased for reinforcement, while other portions may be substantially non-reinforced, i.e., open hole. Here, the substantially vertical section 104 may include a string of casing 108 cemented at an upper portion of the substantially vertical section 104, while horizontal section 106 traversing production zone 111 is open hole.

A tubular string 112 extends from an above ground location (i.e., a surface of the well site) along the wellbore 102, defining an annulus 103 between the tubular string 112 and the wellbore 102 along the open hole portions and with the casing 108 along the cased portions. Tubular string 112 may be included with an upper completion that may provide a conduit for fluid (e.g., production fluid) to travel from the substantially horizontal section 106 to the well's surface. The tubular string 112 can include any number of production tubular sections 116, examples of which are individually indicated at 116a-116d, at various production intervals adjacent to the subterranean formation 110. A corresponding number of packers 118, individually indicated at 118a-118c, can be positioned on opposing sides of production tubular sections to define production intervals (e.g., pipe string 122) and provide fluid seals between the tubular string 112 and the wall of the wellbore 102.

Any number of inflow control devices (ICDs) 120, individually indicated at 120a-120d, may be included for production of formation fluids into the tubular sections 116. The inflow control devices 120 are examples of downhole flow control devices that can be included with the flow control system 140 and which can utilize a turbine as further disclosed below. Generally, inflow control devices are used to control the flow of formation fluid from a production interval into a production tubular section. Generally, an ICD may create a pressure drop, which may be used, for example, to help balance the influx of production fluids from a length of a horizontal section to reduce heel-toe effects, or to slow the flow from a highly permeable zone to delay water or gas breakthrough. Although not required, some ICDs may be autonomous ICDs (i.e., AICDs) that are additionally capable of autonomously restricting undesired fluid or fluid components to a greater extent. ICDs 120 may be used individually to restrict the flow of certain fluid components, thereby collectively increasing a proportion of desired fluid components. For example, the production interval 122 may produce formation fluid having more than one type of fluid component, such as oil, water, carbon dioxide, and natural gas. Each inflow control device 120 uses the properties of different fluid components such as density and/or viscosity to reduce or restrict the flow of fluid of less desirable fluid components (e.g., water and CO₂) into the production tubular section 116 while collectively producing a higher proportion of a more desirable fluid components, such as oil. In some examples, the inflow control devices 120 can be autonomous inflow control devices (AICDs) that can allow

or restrict fluid flow into the production tubular sections 116 based on fluid properties such as density, viscosity, etc., without requiring signals from the well's surface by the well operator.

For case of illustration, FIG. 1 depicts each production tubular section 116 as having an inflow control device (ICD) 120. However, a given zone or production tubular section may have more than one ICD 120, and not every zone or production tubular section may have an inflow control device 120. Also, production tubular sections 116 (and the inflow control devices 120) may be located in substantially vertical section 104 additionally or alternatively to substantially horizontal section 106. Further, any number of production tubular sections 116 with inflow control devices 120 may be used in well system 100. In some examples, production tubular sections 116 with inflow control devices 120 may be disposed in simpler wellbores, such as wellbores 102 having only a substantially vertical section 104. Inflow control devices 120 may be disposed in cased wells or in open-hole environments.

With continued reference to FIG. 1, ICDs 120 may communicate with and/or be controlled by an information handling system 130, which may be disposed at surface and/or at least partially disposed at surface and partially disposed on and/or near an ICD 120 on tubular section 116 downhole. An information handling system 130 may include any instrumentality or aggregate of instrumentalities operable to compute, estimate, classify, process, transmit, broadcast, receive, retrieve, originate, switch, store, display, manifest, detect, record, reproduce, handle, or utilize any form of information, intelligence, or data for business, scientific, control, or other purposes. For example, an information handling system 130 may be a personal computer, a network storage device, or any other suitable device and may vary in size, shape, performance, functionality, and price.

Information handling system 130 may include a processing unit 132 (e.g., microprocessor, central processing unit, etc.) that may process data by executing software or instructions obtained from a local non-transitory computer readable media 134 (e.g., optical disks, magnetic disks). The non-transitory computer readable media 134 may store software or instructions of the methods described herein. Non-transitory computer readable media 134 may include any instrumentality or aggregation of instrumentalities that may retain data and/or instructions for a period of time. Non-transitory computer readable media 134 may include, for example, storage media such as a direct access storage device (e.g., a hard disk drive or floppy disk drive), a sequential access storage device (e.g., a tape disk drive), compact disk, CD-ROM, DVD, RAM, ROM, electrically erasable programmable read-only memory (EEPROM), and/or flash memory; as well as communications media such as wires, optical fibers, microwaves, radio waves, and other electromagnetic and/or optical carriers; and/or any combination of the foregoing. Information handling system 130 may also include input device(s) 136 (e.g., keyboard, mouse, touchpad, etc.) and output device(s) 138 (e.g., monitor, printer, etc.). The input device(s) 136 and output device(s) 138 provide a user interface that enables an operator to interact with ICDs 120 and/or software executed by processing unit 132. Generally, information handling system 130 may communicate to ICDs 120 by communication channel 142. Communication channel 142 may be performed by mud pulse telemetry. For example, Surface equipment, controlled by information handling system 130, may be connected to a production valve or choke. Information handling system 130 may tell/control the production valve/choke to open or

partially close in a specific pattern which in turn alters the flow rate of fluids with wellbore 102. An EICD's turbine generator senses this flow rate changes as a change in RPM of the turbine. The EICD decodes this sequence of RPM changes to determine if it should open, close, choke, etc. This sequence may be specific to a certain EICD in tubular string 112 or maybe commanding a group of pre-programmed EICDs to respond to the same command.

Additionally, an ICD may also operate autonomously if pre-programmed. The ICD may respond to changes in wellbore 102 based upon things like turbine RPM. ICD may also have sensors onboard such as a water cut sensor that could sense water or gas and could trigger ICD to close or choke. Using the systems and methods described above, information handling system 130 may enable an operator to increase or decrease flow of fluid through ICDs 120, as discussed below.

FIG. 2 illustrates an ICD 120 in accordance with one or more embodiments of the present disclosure. As illustrated, 20 a fluid 200 (which may comprise one or more fluids, such as oil and water, liquid water and steam, oil and gas, gas and water, oil, water and gas, etc.) may be filtered by a well screen (at tubular section 116) and may then flow into an inlet flow path 202 of ICD 120. Fluid 200 may comprise one 25 or more undesired or desired fluids. Both steam and water may be combined in fluid 200. As another example, oil, water and/or gas may be combined in fluid 200. The flow of fluid 200 through ICD 120 may be resisted due to diameter of fluid passageway 204. In examples, fluid passageway 204 30 may be tubing, voids within a housing, three dimensional printed paths within a material, gun drilled flow paths, and/or the like. Additionally, it should be noted that fluid passageway 204 may be any suitable shape and/or dimension to allow for fluid to flow from outside ICD to the inside 35 tubular string 112 in which and ICD 120 may be disposed (e.g., referring to FIG. 1). This may control the flow rate of fluid 200 flowing through ICD 120. Fluid 200 may then be discharged from ICD 120 to an interior of tubular string 112 via an outlet flow path 206. As used herein, the direction of 40 the flow of fluid 200 from inlet flow path 202 to outlet flow path 206 be reversed, such as during injection applications, through ICD 120 such that the flow of fluid 200 may originate at outlet flow path 206 and traverse to inlet flow path 202, where fluid 200 may be dispelled into formation 45 110 and/or wellbore 102.

In other examples, well screens may not be used in conjunction with ICD 120 (e.g., in injection operations) and fluid 200 may flow in an opposite direction through the various elements of well system 100 (e.g., in injection operations). In other examples, a single ICD 120 may be used in conjunction with multiple well screens or multiple ICDs 120 may be used with one or more well screens. Thus, fluid 200 may be received from or discharged into regions of wellbore 102 other than annulus or tubular string 112. 50 Additionally, flow of fluid 200 may flow through ICD 120 prior to flowing through the well screen and any other components may be interconnected upstream or downstream of the well screen and/or any ICD 120. Thus, the principles of this disclosure are not limited at all to the details of the example depicted in the figures and described herein. Further, additional components (such as shrouds, shunt tubes, lines, instrumentation, sensors, inflow control devices, etc.) 55 may also be used in accordance with the present disclosure, if desired.

With continued reference to FIG. 2, ICD 120 may include various passages and devices for performing various functions, as described more fully below. In addition, ICD 120

may at least partially extend circumferentially about tubular string 112, or ICD 120 may be formed in a wall of a tubular structure interconnected as part of tubular string 112. In other examples, ICD 120 may not extend circumferentially about tubular string 112 or be formed in a wall of a tubular structure. For example, ICD 120 may be formed in a flat structure, etc. ICD 120 may be in a separate housing that is attached to tubular string 112, or it may be oriented so that the axis of outlet flow path 206 is parallel to the axis of tubular string 112. ICD 120 may be on a logging string, production string, drilling string, coiled tubing, or other tubular string or attached to a device that is not tubular in shape. Any orientation or configuration of ICD 120 may be used in keeping with the principles of this disclosure.

As illustrated in FIG. 2, ICD 120 comprises inlet flow path 202 to receive fluid 200 into ICD 120 and outlet flow path 206 to send fluid 200 out of ICD 120. When fluid exits ICD 120, fluid 200 may, for example, enter into the interior of a tool body or out of the exterior of a tool body used in conjunction with ICD 120. Additionally, ICD 120 may comprise one or more power sources. For example, ICD 120 may include a power generator 208 and/or one or more power storage devices 210. Power generator 208 may be used to generate power for ICD 120, and power storage devices 210 may be used to provide stored power for ICD 120 and/or store power generated by power generator 208. In one embodiment, power generator 208 may include a turbine and may be able to generate power from fluid 200 received into inlet flow path 202 and flowing through ICD 120. Additionally, ICD 120 may comprise intermediary flow positions prior to closure to adjust flowrate, along with a regulator on the primary flow path to ensure turbine RPM of power generator 208 does not fall too low for minimum power demand. In examples, an intermediary flow position may be performed in an EICD that may utilize a device such as a needle valve. As the needle valve gets closer to the exit path, the flow area is reduced. The EICD may also have multiple inlets and the valve could be closing off inlets as it strokes to provide intermediate choking. Thus, as the valve moves, it must change flow area in order to create intermediate flow positions/choking effect.

Power generator 208 may additionally or alternatively include other types of power generators, such as a flow induced vibration power generator and/or a piezoelectric generator, to generate power from the fluid received into ICD 120 and/or from other energy sources present downhole (e.g., temperature and/or pressure sources).

Power storage devices 210 may be included within electronics for ICD 120 and may be used to provide stored power. In one embodiment, power storage devices 210 may be able to store power generated by power generator 208 and provide this stored power for ICD 120. Power storage device 210 may comprise a capacitor (e.g., super capacitor), battery (e.g., rechargeable battery), and/or any other type of power storage device known in the art. In one or more embodiments, devices, components, and/or the like of ICD 120 may require power generated by power generator 208. Additionally, power storage device 210 may be used to store power, and then supplement power generator 208 when running devices, components, and/or the like that may be housed and/or connected to ICD 120.

FIG. 3 illustrates an ICD 120 with an actuator 300. In this example, ICD 120 may comprise an actuator 300 which may control the flow of fluid 200 into tubular string 112. As illustrated, fluid 200 may enter into ICD 120 through inlet flow path 202. During operations, fluid 200 may flow into tubular string 112 due to a pressure imbalance between the

outside of tubular string 112 and inside of tubular string 112, as discussed above. In one or more examples, the flow of fluid 200 may be stopped utilizing actuator 300.

Actuator 300 may control or adjust an inflow rate of fluid 200 received into ICD 120 through inlet flow path 202. Additionally, actuator 300 may control or adjust the restriction of fluid 200 received into ICD 120 by controlling and/or adjusting a drop in pressure between inlet flow path 202 and outlet flow path 206. For example, actuator 300 may be positioned or included within ICD 120 to extend into and retract from fluid flow path 302 in fluid passageway 204, which may extend and be formed through ICD 120. To increase the inflow rate of fluid 200 or decrease the inflow fluid restriction or pressure drop across ICD 120, actuator 300 may retract to enable more fluid to flow through fluid flow path 302 of ICD 120. To decrease the inflow rate of fluid 200 or increase the inflow fluid restriction or pressure drop across ICD 120, actuator 300 may extend to restrict the fluid flow through fluid flow path 302 of ICD 120. Further, in one or more embodiments, the actuator 300 may be used to fully stop or inhibit the fluid flow through fluid flow path 302 of ICD 120. For example, if ICD 120 is turned or powered off, actuator 300 may fully extend to prevent fluid flow through fluid flow path 302 of ICD 120. Accordingly, actuator 300 may be used as or include an adjustable valve to be in a fully open position, a fully closed position, or an intermediate position to control the flow rate of fluid 200 through ICD 120. Further, in one or more embodiments, the control or adjustment of the inflow rate of fluid, the restriction of fluid inflow, or the pressure drop may all be parameters related to each other. Accordingly, as used herein, when referring to control or adjustment of one parameter, such as the inflow rate of fluid, may also be referring to control or adjustment of another parameter without departing from the scope of the present disclosure.

Actuator 300 may comprise a mechanical actuator (e.g., a screw assembly), an electrical actuator (e.g., piezoelectric actuator, electric motor), a hydraulic actuator (e.g., hydraulic cylinder and pump, hydraulic pump), a pneumatic actuator, and/or any other type of actuator known in the art. As illustrated, actuator 300 may comprise a shaft 304, crown 306, and a tip 308 that may at least be partially angled. The angling of tip 308 may allow for the tip to form a fluid tight seal with seat 310. As illustrated, actuator 300 may be disposed within chamber 312. Generally, chamber 312 may be dimensioned to receive shaft 304 of actuator 300 with additional space to allow for fluid 200 to pass by shaft 304 and to fluid passageway 204.

Additionally, a spring 316 may be disposed around actuator 300. As illustrated in FIG. 3, actuator 300 may slip within the coils of spring 316. In examples, spring 316 may be disposed on one end against the crown 306 and disposed at the opposite end against retaining ring 318. Although a retaining ring 318 is illustrated, the inner diameter of chamber 312 may be reduced to act and function like retaining ring 318 to provide a structure upon which spring 316 may be disposed. During operations, as described above and below, as actuator 300 moves toward seat 310, spring 316 may compress. Spring 316 may remain compressed as fluid 200 flowing from formation through inlet flow path 202 applies pressure to actuator 300. If pressure within borehole 116 is reduced, which may reduce the pressure exerted by fluid 200 against actuator 300 through inlet flow path 202, then spring 316 may exert a force against crown 306 and retaining ring 318, which may move actuator 300 away from

seat 310 and toward motor 320. As illustrated, actuator 300 may connect to a motor 320 through a detachable connector 314.

Motor 320 may be an AC, DC (brushed or brushless), or stepper motor. As noted above, actuator 300 may be connected to motor 320 by a detachable connector 314. Detachable connector 314 may be a magnetic coupling, collet connection, or friction connection. During operations, motor 320 may operate and move shaft 304 and tip 308 of actuator 300 toward seat 310, which may decrease flow rate of fluid 200 into tubular string 112. In examples, as actuator 300 gets close to seat 310, the velocity of fluid at tip 308 of actuator 300 will increase. This increase in velocity creates a low-pressure zone. This low-pressure zone will pull on actuator 300 to set it to seat 310. Detachable connector 314 may allow for actuator 300 to detach from motor 320. Using the flow of fluid 200 from inlet flow path 202 through fluid flow path 302 to outlet flow path 206, actuator 300 may be set to seat 310. This may block all flow of fluid 200 through ICD 120. Existing EICDs, once closed, do not have the capability to be opened as they are a one-time cycle. However, fully closed capability that is both closed and reopened remotely may improve the oil/water production ratio for EICD while streamlining field operations. For the methods and systems described herein, an injection flow operation may be performed to reverse the actuation and reset ICD 120. During an injection operation, fluid 200 may be forced down and within pipe string 122 and out to formation 110 through ICDs 120 (e.g., referring to FIG. 1). In this operation, the fluid flow from within pipe string 122 would press against actuator 300 that is set in seat 310. The pressure from the fluid flow would unseat actuator 300 and detachable connector 314 would allow for actuator 300 to re-connect to motor 320. Once reconnected, actuator 300 may allow for fluid flow to resume normal operations after the injection operation has ended. This may allow for generation of power through a power generator 208 (e.g., referring to FIG. 2) which may be used by motor 320 to further retract actuator 300 within chamber 312. This may allow for fluid flow to increase in fluid passageway 204 through fluid flow path 302 to resume formation production operations.

FIG. 4 illustrates a schematic of an electric inflow valve system 400 that may comprise one or more ICDs 120 that may be utilized in a formation production operation. As noted above, ICD 120, and more particularly actuator 300, may be used to control or adjust an inflow rate of fluid 200 received into ICD 120 through inlet flow path 202, control or adjust the restriction of fluid inflow received into ICD 120, and/or control or adjust a drop in pressure across ICD 120 (e.g., referring to FIGS. 3 and 4). The inflow rate of fluid 200 received into ICD 120 may be controlled by information handling system 130, which may transmit one or more control signals downhole to operate one or more ICDs 120. A control signal may be sent to ICD 120 from information handling system 130 that may be disposed uphole or upstream of ICD 120, or even on or close to surface. Control signals may be sent to ICD 120 through the flow rate of mud within tubular string 112, and more particularly by selectively fluctuating and varying the flow rate of mud received by ICD 120. A profile or pattern of flow rate fluctuations may be used to indicate a unique control signal, such as with communications involving flow rate telemetry. Accordingly, information handling system 130, controlling the flow rate of mud through any number of devices known to one of ordinary skill in the art, may be able to encode one or more control signals through flow rate fluctuations of the mud, and a receiver disposed on ICD 120 may measure the flow rate

of the mud. The receiver may be disposed on and/or near ICD 120 and may be an information handling system 130 or at least a part of information handling system 130 and may be able to decode one or more controls signals through the flow rate fluctuations of the mud. Information handling system 130 may transmit a control signal by generating flow rate fluctuations of the mud uphole or downstream of ICD 120. Accordingly, to generate the flow rate fluctuations, information handling system 130 may control a choke, a bypass around a choke, a valve, a pump, or control the backpressure of the mud at the surface, thereby selectively generating fluctuations in the flow rate of the mud through tubular string 112 which may comprise one or more ICDs 120.

With continued reference to FIG. 4, information handling systems 130 disposed on and/or near ICD 120 may control any number of devices and/or their operations. For example, information handling system 130 may control the operations of power generator 208 disposed within an ICD 120. It should be noted that power generator 208 and actuator 300 may be disposed on the same or separated ICDs 120. Additionally, the same or another information handling system may control the operations of actuator 300. Generally, Formation production operations, using one or more ICDs 120, may be electric inflow control device(s) (EICD) that operate actuator 300. EICDs consume power downhole to move actuator 300. The power consumed may be generated by power generator 208. However, EICDs may have limited coupling force due to size constraints and magnetic arrays utilized to move actuator 300 in an EICD may be hindered by downhole pressure experienced within a formation. FIG. 4 illustrates a schematic that allows Formation production operations to be performed at higher downhole pressures and improve the available force to move actuator 300 while also improving the debris tolerance of the system. Debris tolerance may be increased due to the force available within ICD 120. With small actuation forces, debris or other friction adding elements may hinder movement. With big actuation forces, such as the forces described herein, debris is easily moved to the side.

The schematic in FIG. 4 illustrates motor 320, controlled by information handling system 130 disposed on or near ICD 120 or at surface. As illustrated, information handling system 130 may be connected to power generator 208 and/or motor 320 through communication channel 142. Communication channel may allow for communication between information handling system 130 and power generator 208 and/or motor 320 through the flow rate of mud or production fluid, or production fluid within tubular string 112, as described above. Additionally, the production rate of mud or production fluid may be changed and correspond to RPM changes by one or more turbines. During operations, information handling system 130 may instruct motor 320 to move actuator 300, through detachable connector 314, either toward or away from seat 310 utilizing the methods and systems discussed above. As noted above, as actuator 300 moves toward seat 310, the flow of fluid 200 through ICD 120 may slow the movement of fluid 200 to the inner diameter of tubular string 112 (e.g., referring to FIG. 1).

As shown in FIG. 5, actuator 300 has been seated to seat 310, preventing fluid 200 from moving into the inner diameter of tubular string 112. For actuator 300 to be set to seat 310, as discussed above, actuator 300 has detached from motor 320 through detachable connector 314. Additionally, as described above, as actuator 300 moves toward seat 310, spring 316 may compress. Spring 316 may remain compressed as fluid 200 flowing from formation through inlet

flow path 202 applies pressure to actuator 300. If pressure within borehole 116 is reduced, which may reduce the pressure exerted by fluid 200 against actuator 300 through inlet flow path 202, then spring 316 may exert a force against crown 306 and retaining ring 318, which may move actuator 300 away from seat 310 and toward motor 320. In other examples, to move actuator 300 away from seat 310, as noted above, an injection operation may be performed to increase the pressure within pipe string 122 to force fluid 200 out of pipe string 122 and into formation 110 through ICD 120. The pressure exerted from within pipe string 122 may unseat actuator 300 from seat 310. The detachable connector 314 may then allow actuator 300 to reattach to motor 320. With fluid flow reestablished, power may be created by power generation 208. This may allow for power to be utilized by motor 320 to move actuator 300 further away from seat 310 and further increase fluid flow.

Current wireless, self-power generating EICDs cannot 100% close without some form of stored energy. Stored energy has inherent risks and complexity. Another method for 100% closure is with a mechanically shifted sleeve. However, a mechanically shifted sleeve requires intervention with coil tubing, slickline, and/or the like, which has cost, and time associated with it. The methods and systems discussed above allow for a mechanical means of 100% closure of an EICD while allowing for the EICD to be reopened later without stored energy devices or intervention. The various systems, apparatus, methods, and other constructs may include any suitable combination of the features disclosed herein, including one or more of the following statements.

Statement 1: An inflow control device for a well that may comprise a chamber, wherein the chamber comprises a seat, a fluid passageway fluidly connected to the chamber, an actuator disposed within the chamber, and a motor at least partially disposed in the chamber and detachably connected to the actuator by a detachable connector.

Statement 2: The inflow control device of statement 1, wherein the detachable connector is a magnetic coupling.

Statement 3: The inflow control device of statements 1 or 2, wherein the motor is AC, DC (brush or brushless), or stepper motor.

Statement 4: The inflow control device of any previous statements 1-3, further comprising an information handling system in communication with the motor.

Statement 5: The inflow control device of statement 4, wherein the information handling system is disposed at surface.

Statement 6: The inflow control device of any previous statements 4 or 5, wherein the information handling system is disposed downhole on a tubing string.

Statement 7: The inflow control device of any previous statements 4-6, wherein the information handling system is at least partially disposed downhole on a tubing string and at least partially disposed at surface.

Statement 8: The inflow control device of any previous statements 1-4, wherein the actuator comprises a shaft and an angled tip.

Statement 9: The inflow control device of statement 8, wherein the angled tip is configured to be set within the seat.

Statement 10: The inflow control device of any previous statements 1-4 or 8, further comprising a power generator.

Statement 11: The inflow control device of statement 10, further comprising an information handling system, wherein the information handling system is in communication with the power generator and the motor.

Statement 12: The inflow control device of statement 11, wherein the power generator creates power in which the motor utilizes to operate.

Statement 13: A method may comprise receiving a fluid 5 from a formation with an inflow control device (ICD) disposed on a tubular string within a formation. The ICD may comprise a chamber, wherein the chamber comprises a seat, a fluid passageway connected to the chamber, an actuator disposed within the chamber, and a motor at least 10 partially disposed in the chamber and detachably connected to the actuator by a detachable connector. The method may further comprise stopping flow of the fluid through the ICD by seating the actuator to the seat after the actuator has detached from the motor by the detachable connector.

Statement 14: The method of statement 13, wherein the detachable connector is a magnetic coupling.

Statement 15: The method of statement 14 or 15, wherein the motor is AC, DC (brush or brushless), or stepper motor.

Statement 16: The method of any previous statements 20 13-15, further comprising an information handling system in communication with the motor, wherein the information handling system is disposed at surface, disposed downhole on a tubing string, or at least partially disposed at surface.

Statement 17: The method of any previous statements 25 13-16, wherein the actuator comprises a shaft and an angled tip.

Statement 18: The method of statement 17, wherein the angled tip is configured to be set within the seat.

Statement 19: The method of any previous statements 30 13-17, further comprising a power generator.

Statement 20: The method of statement 19, further comprising an information handling system, wherein the information handling system is in communication with the power generator and the motor.

The preceding description provides various examples of the systems and methods of use disclosed herein which may contain different method steps and alternative combinations of components. It should be understood that, although individual examples may be discussed herein, the present disclosure covers all combinations of the disclosed examples, including, the different component combinations, method step combinations, and properties of the system. It should be understood that the compositions and methods are described in terms of "comprising," "containing," or "including" various components or steps, the compositions and methods may also "consist essentially of" or "consist of" the various components and steps. Moreover, the indefinite articles "a" or "an," as used in the claims, are defined herein to mean one or more than one of the elements that it introduces.

For the sake of brevity, only certain ranges are explicitly disclosed herein. However, ranges from any lower limit may be combined with any upper limit to recite a range not explicitly recited, as well as ranges from any lower limit 55 may be combined with any other lower limit to recite a range not explicitly recited, in the same way, ranges from any upper limit may be combined with any other upper limit to recite a range not explicitly recited. Additionally, whenever a numerical range with a lower limit and an upper limit is disclosed, any number and any included range falling within the range are specifically disclosed. In particular, every range of values (of the form, "from about a to about b," or, equivalently, "from approximately a to b," or, equivalently, "from approximately a-b") disclosed herein is to be understood to set forth every number and range encompassed within the broader range of values even if not explicitly recited. Thus, every point or individual value may serve as

11

its own lower or upper limit combined with any other point or individual value or any other lower or upper limit, to recite a range not explicitly recited.

Therefore, the present examples are well adapted to attain the ends and advantages mentioned as well as those that are inherent therein. The particular examples disclosed above are illustrative only and may be modified and practiced in different but equivalent manners apparent to those skilled in the art having the benefit of the teachings herein. Although individual examples are discussed, the disclosure covers all combinations of all of the examples. Furthermore, no limitations are intended to the details of construction or design herein shown, other than as described in the claims below. Also, the terms in the claims have their plain, ordinary meaning unless otherwise explicitly and clearly defined by the patentee. It is therefore evident that the particular illustrative examples disclosed above may be altered or modified and all such variations are considered within the scope and spirit of those examples. If there is any conflict in the usages of a word or term in this specification and one or more patent(s) or other documents that may be incorporated herein by reference, the definitions that are consistent with this specification should be adopted.

What is claimed is:

1. An inflow control device for a well, comprising:
a chamber, wherein the chamber comprises a seat;
a fluid passageway fluidly connected to the chamber;
an actuator disposed within the chamber;
a motor at least partially disposed in the chamber and
detachably connected to the actuator by a detachable
connector, wherein the motor is configured to detach
from the actuator causing the actuator to press against
the seat to close the fluid passageway.
2. The inflow control device of claim 1, wherein the
detachable connector is a magnetic coupling.
3. The inflow control device of claim 1, wherein the motor
is AC, DC (brush or brushless), or stepper motor.
4. The inflow control device of claim 1, further comprising
an information handling system in communication with
the motor.
5. The inflow control device of claim 4, wherein the
information handling system is disposed at surface.
6. The inflow control device of claim 4, wherein the
information handling system is disposed downhole on a tubing
string.
7. The inflow control device of claim 4, wherein the
information handling system is at least partially disposed
downhole on a tubing string and at least partially disposed
at surface.

12

8. The inflow control device of claim 1, wherein the
actuator comprises a shaft and an angled tip.
9. The inflow control device of claim 8, wherein the
angled tip is configured to be set within the seat.
10. The inflow control device of claim 1, further comprising
a power generator.
11. The inflow control device of claim 10, further comprising
an information handling system, wherein the information
handling system is in communication with the power
generator and the motor.
12. The inflow control device of claim 11, wherein the
power generator creates power which the motor utilizes to
operate.
13. A method, comprising:
receiving a fluid from a formation with an inflow control
device (ICD) disposed on a tubular string within a
formation, wherein the ICD comprises:
a chamber, wherein the chamber comprises a seat;
a fluid passageway connected to the chamber;
an actuator disposed within the chamber; and
a motor at least partially disposed in the chamber and
detachably connected to the actuator by a detachable
connector; and
stopping flow of the fluid through the ICD by seating the
actuator to the seat after the actuator has detached from
the motor by the detachable connector.
14. The method of claim 13, wherein the detachable
connector is a magnetic coupling.
15. The method of claim 13, wherein the motor is AC, DC
(brush or brushless), or stepper motor.
16. The method of claim 13, further comprising an
information handling system in communication with the
motor, wherein the information handling system is disposed
at surface, disposed downhole on a tubing string, or at least
partially disposed at surface.
17. The method of claim 13, wherein the actuator com-
prises a shaft and an angled tip.
18. The method of claim 17, wherein the angled tip is
configured to be set within the seat.
19. The method of claim 13, further comprising a power
generator.
20. The method of claim 19, further comprising an
information handling system, wherein the information han-
dling system is in communication with the power generator
and the motor.
